UNITED STATES PATENT OFFICE.

JULIUS HEZLER, OF POUGHKEEPSIE, NEW YORK.

FOLDING BOX.

1,204,370.

Specification of Letters Patent. Patented Nov. 14, 1916.

Application filed March 14, 1914. Serial No. 824,737.

To all whom it may concern:

Be it known that I, JULIUS HEZLER, a subject of the King of Hungary, residing at Poughkeepsie, in the county of Dutchess and State of New York, have invented certain new and useful Improvements in Folding Boxes, of which the following is a specification, reference being had therein to the accompanying drawing.

10 This invention relates to folding boxes and has for its objects to provide a box of such class, in a manner as hereinafter set forth, which can easily be folded to a compact position or extended to an upright position when occasion so requires.

15 Further objects of the invention are to provide a folding box which is simple in its construction and arrangement, strong, durable, efficient and convenient in its use, readily assembled, and comparatively inexpensive to manufacture.

20 With the foregoing and other objects in view the invention consists of the novel construction, combination and arrangement of 25 parts as hereinafter more specifically described and illustrated in the accompanying drawings wherein is shown an embodiment of the invention, but it is to be understood that changes, variations and modifications 30 can be resorted to which come within the scope of the claim hereunto appended.

35 In the drawings wherein like reference characters denote corresponding parts throughout the several views: Figure 1 is an elevation partly in section, the sectional portion of said figure being taken on line C—D of Fig. 2; Fig. 2 is an elevation partly in section, the sectional portion of said figure being taken on line A—B of Fig. 1; 40 Fig. 3 is an elevation of the box when folded, and partly in section, the sectional portion of said figure corresponding to a section taken on line A—B of Fig. 1 when the box is folded; Fig. 4 is a section of a corner of the box taken on line C—D of Fig. 2; and Fig. 5 is an elevation of the box when folded, and partly in section, the sectional portion of said figure being taken on line E—F of Fig. 1 when the box is folded.

45 Referring to the drawings in detail, 6 denotes the lower section of the front wall of the box, and 7 the lower section of the rear wall of the box, while 8 denotes the lower section of one end wall, and 9 the lower section of the other end wall.

The inner face of the section 6 near its

lower end is provided with an integral rib 10, and the inner face of the section 7 is provided with an integral rib 11, and abutting against the lower faces of the ribs 10 and 11, and against the inner faces of the sections 6—7 is the bottom 12 of the box. The rib 11 is of a greater height than the rib 10. Secured to the rib 10, by the hold-fast devices 12^a, is a series of hinge sections 13 of leaf construction, and each of said sections 13, has its lower end bent at right angles as at 14, and fixedly secured by a hold-fast device 15 to the upper face of the bottom 12. The upper face of the bottom 12 is provided with pockets 16 for the angular portions 14 of the sections 13, and said pockets 16 are of such depth whereby the angular portions 14 will be flush with the upper face of the bottom 12. Each of the sections 13 at its upper end is provided with barrels 17, which are arranged in alinement with barrels 18 of hinge sections 19 of leaf construction, and the said sections 19 are countersunk in the inner face of the upper front wall section 20. The barrels 17—18 have extending therewith a pivoted pin 21 whereby the sections 13 are hinged to the sections 19. When the front wall section 20 is swung upwardly, it bears against the inner face of the upper portion of the section 6, under such conditions the lower section 6 of the front wall overlaps the upper section 20 when the latter is extended.

Secured to the rib 11 by hold-fast devices 22 are hinge sections 23 of leaf construction, and the lower portion of said sections 23 are bent at right angles and countersunk in the upper face of the bottom 12 as at 24. The angular portions of the sections 23 are fixedly secured to the bottom by hold-fast devices 25. The upper portion of each of the sections 23 is provided with a plurality of barrels 26 with which aline barrels 27 carried by hinge sections 28 of leaf construction. The sections 28 are fixedly secured to the inner face of the upper section 29 of the rear wall through the medium of hold-fast devices 30. When the upper section 29 is extended it abuts against the inner face of the lower section 7 whereby said lower section 7 will overlap said upper section 29.

The sections 6 and 7 provide what may be termed brace supports for the sections 20 and 29 when these latter are extended and said sections 20—29 when extended rest upon the upper face of the ribs 10—11.

When the sections 20—29 are folded inwardly, the section 29 extends over the section 20 and the said section 20 further extends over the upper sections 31—32 of the end walls. The lower sections of the end walls are indicated at 33—34 and the section 31 is hinged as at 34^a, to a rib 35 formed on the inner face of the section 33, and against which abuts the bottom 12. The section 32 is hinged as at 36 to a rib 37 formed on the inner face of the section 34 and against which the bottom 12 abuts. One leaf of each of the hinge connections between sections 31—33 and 32—34 is countersunk in and fixedly secured to the bottom 12, as shown at 38.

When the sections 31—32 are folded, they are mounted upon the upper face of the bottom 12, and when extended abut against the inner face of the sections 33—34, and the said sections 33—34 form brace supports for the sections 31—32 when these latter are extended.

The upper section of each of the end walls is provided at each end with a hook, the shank of the hook is indicated at 39 and is countersunk in the inner face of its respective wall, and is further secured to its respective wall by a hold-fast device 40. The bill of the hook which is indicated at 41 is spaced from the edge of its respective wall, and each of said hooks is of a length equal to the height of that section of the end wall to which it is secured.

The upper section of the front wall, as well as the upper section of the rear wall, has provided at each end a keeper 42 formed

with a shank 43 which is fixedly secured to its respective wall by a hold-fast device 44. The keeper is of a length equal to the height 40 of that section of the wall to which it is secured, and the said keepers 42 are adapted to receive the bills 41 of the hooks when the upper sections of the walls of the box are extended and as clearly illustrated in 45 Fig. 4, and by the engagement of the hooks with the keepers, the said upper sections of the walls of the box are maintained in an upright position. A cover for the body portion of the box is indicated at 45.

What I claim is:—

A folding box comprising lower, front, rear and end wall sections, each of which has its inner face provided with a rib, the rib of the lower section of the front wall 55 being of less height than the rib of the lower section of the rear wall, a bottom positioned against the lower faces of said ribs, lower, end, front and rear wall sections, hinge connections secured to said upper sections 60 and to said ribs and further extended and secured to said bottom, said upper sections when extended abutting against the inner faces of said lower sections, hooks secured to the upper end of each end wall and having tongues adapted to interlock with the adjoining wall, and a cover engaging said upper sections when the walls are extended.

In testimony whereof I affix my signature in the presence of two witnesses.

JULIUS HEZLER.
